CLOTHESPIN RACK AND CONTAINER

John J. Spissell, Elmont, N. Y.

Application January 27, 1950, Serial No. 140,876

2 Claims. (Cl. 312—280)

1

This invention relates to a novel construction of clothes pin supporting rack and container for use when hanging laundry on a line or in removing laundry therefrom and which may be demountably supported in a convenient position on the clothesline or on a clothesline supporting pulley.

More particularly, it is an aim of the present invention to provide a structure having a rack portion upon which clothes pins may be positioned to enable them to be conveniently removed for use without requiring the user to reach into a receptacle to extract a clothes pin therefrom, and which structure is embodied as a part of a receptacle into which the clothes pins may be thrown after being removed from a clothesline and before being replaced upon the clothes pin supporting rack structure for reuse.

Still a further object of the invention is to provide a clothes pin rack and holder which will reduce the labor involved in securing laundry on a clothesline and which will afford a convenient means for holding clothes pins while not in use and preparatory to being used.

Various other objects and advantages of the invention will hereinafter become more fully apparent from the following description of the drawing, illustrating a presently preferred embodiment thereof, and wherein:

Figure 1 is a top plan view of the invention;

Figure 2 is a fragmentary side elevational view thereof, and

Figure 3 is a vertical sectional view taken substantially along a plane as indicated by the line 3—3 of Figure 2 and showing the bale or handle in an inoperative position.

Referring more specifically to the drawing, the clothes pin holder or clothes pin rack and container, comprising the invention, is designated generally 5 and includes an opened top container or receptacle 6 preferably having a substantially flat bottom 7 and an upstanding cylindrical side wall 8. The container 6 has an annular flange 9 which extends outwardly and upwardly from the periphery of the bottom 7 and from the lower edges of the side wall 8 and which preferably forms an integral part thereof. The annular flange 9 extends upwardly in diverging relationship to the receptacle wall 8. A relatively wide annular band or ring 10 is disposed around and spaced outwardly from the upper portion of the side wall 8 and has its bottom edge disposed substantially above the top edge of the flange 9. The ring 10 is supported concentrically to the container wall 8 by a plurality of circumferentially spaced supporting arms 11 which are pref-

2

erably formed integral therewith and with the flange 9 and receptacle wall 8. Each supporting arm 11 is joined intermediate of its ends with a portion of the ring 10, adjacent the bottom edge of said ring and has a substantially straight depending lower end which joins with a portion of the upper edge of the flange 9. The upper end 12 of each supporting arm 11 is curved inwardly from the ring 10 and joins with a portion of the receptacle wall 8.

10 The clothes pin holder 5 includes two double headed rivets 13 each of which extends between the container wall 8 and a portion of the ring 10 and is anchored to the wall and ring by its headed ends engaging the remote sides of the wall and ring. The two rivets 13 are arranged in diametrical alignment and each rivet provides a journal for a sleeve 14, which is disposed between the ring 10 and wall 8. The sleeves 14 are formed on the ends of a substantially semi-circular bale 15. A hook 16 projects outwardly from the intermediate portion of the bale 15 and has a restricted shank end 17 which is swivelly mounted in an opening 18 of the bale 15.

15 From the foregoing it will be readily apparent that a number of clothes pins 19, of a conventional construction, may be mounted around the upper portion of the wall 8, which forms one rack portion, another series of clothes pins 19 may be mounted, likewise in an upright position around the ring 10 and a third series of clothes pins 19 may be mounted in an inclined position around the annular flange 9 and in upwardly and outwardly diverging relationship with respect to the container wall 8. The wall 8, ring 10 and flange 9 are of sufficient thickness to frictionally engage in the slots of the clothes pins 19 to retain the clothes pins on said rack portions and against casual disengagement therefrom. Accordingly, three rings of clothes pins 19 may be mounted on the holder 5 after which the holder may be carried to a clothesline and suspended detachably thereon or on a pulley thereof, not shown, by engagement of the hook 16 therewith so that the clothes pins 19 mounted on the rack portions 8, 9 and 10 will be conveniently located to be individually detached from the holder 5 as they are required for use. In removing the clothes pins 19 from a clothesline they may be dropped into the receptacle 6 to avoid delay and thereafter replaced upon the rack portions 8, 9 and 10 before it is desired to use them again.

20 The clothes pin holder 5 may be formed of any suitable material, preferably being molded from a plastic. As illustrated in Figure 3, the bale or handle 15, by which the holder 5 is normally car-

ried, is of a size so that it may be swung downwardly between the wall 8 and ring 10 and disposed with the hooks 16 engaging over the ring 10, as illustrated in Figure 3, when the holder 5 is not in use.

Various modifications and changes are contemplated and may obviously be resorted to, without departing from the spirit or scope of the invention as hereinafter defined by the appended claims.

I claim as my invention:

1. A clothes pin holder comprising an open top receptacle for clothes pins having a cylindrical side wall extending from top to bottom of the receptacle, a relatively wide annular band disposed concentrically around and spaced from the upper portion of the receptacle side wall, supporting arms connected to and extending between the receptacle wall and annular band and supporting the annular band on the receptacle and above the bottom thereof, said annular band and the upper portion of the cylindrical wall forming rack portions for supporting two rings of clothes pins in substantially upright positions, and an annular flange extending upwardly and outwardly from the bottom portion of said receptacle and disposed in upwardly diverging relationship to its cylindrical side wall to form an additional clothes pin engaging rack, the upper edge of said annular flange being disposed beneath and spaced from the bottom edge of the annular band.

2. A clothes pin holder comprising an open top

receptacle for clothes pins having a cylindrical side wall extending from top to bottom of the receptacle, a relatively wide annular band disposed concentrically around and spaced from the upper portion of the receptacle side wall, supporting arms connected to and extending between the receptacle wall and annular band and supporting the annular band on the receptacle and above the bottom thereof, said annular band and the upper portion of the cylindrical wall forming rack portions for supporting two rings of clothes pins in substantially upright positions, and an annular flange extending upwardly and outwardly from the bottom portion of said receptacle and disposed in upwardly diverging relationship to its cylindrical side wall to form an additional clothes pin engaging rack, the upper edge of said annular flange being disposed beneath and spaced from the bottom edge of the annular band.

JOHN J. SPISSELL.
